[57] CLAIM

The ornamental design for a refuse receptacle, substantially as shown and described.

DESCRIPTION

FIG. 1 is a front perspective view of a refuse receptacle, showing our new design.

FIG. 2 is a left side view thereof, the right side being a mirror image.

FIG. 3 is a top plan view thereof.

FIG. 4 is a bottom plan view thereof.

FIG. 5 is a rear plan view thereof.

FIG. 6 is a front elevational view thereof.
